Primary Examiner—Cathron C. Brooks*Assistant Examiner*—Ricky Pham(74) *Attorney, Agent, or Firm*—Cook, Alex, McFarron, Manzo, Cummings & Mehler Ltd.(57) **CLAIM**

The ornamental design for a foldable spoon, as shown and described.

DESCRIPTION

FIG. 1 is a top perspective view of a foldable spoon showing the new design in a folded orientation;

FIG. 2 is a top plan view thereof;

FIG. 3 is a bottom plan view thereof;

FIG. 4 is a side elevational view thereof;

FIG. 5 is an opposite side elevational view thereof;

FIG. 6 is an end elevational view thereof;

FIG. 7 is an opposite end elevational view thereof;

FIG. 8 is a top perspective view thereof showing the new design in an unfolded orientation;

FIG. 9 is a bottom plan view of FIG. 8;

FIG. 10 is a top plan view thereof;

FIG. 11 is a side elevational view thereof;

FIG. 12 is an opposite side elevational view thereof;

FIG. 13 is an end elevational view thereof; and,

FIG. 14 is an opposite elevational view thereof.
